UNITED STATES PATENT OFFICE.

GEORGE W. DUNSWORTH, OF HOUSTON, TEXAS.

DRILL.

Application filed April 26, 1921. Serial No. 464,626.

To all whom it may concern:

Be it known that I, GEORGE W. DUNSWORTH, a citizen of the United States, residing at Houston, in the county of Harris 5 and State of Texas, have invented certain new and useful Improvements in a Drill, of which the following is a specification.

This invention relates to new and useful improvements in a drill.

10 One object of the invention relates to an improved form of drill which may be used either in drilling by the cable-tool process or by the rotary process and when used in connection with a rotary is also adapted for 15 use as an underreamer.

Another object is to provide a bit which can be readily collapsed for withdrawal from the well.

With the above and other objects in view 20 this invention has particular relation to certain novel features of construction, operation and arrangement of parts, an example of which is given in this specification and illustrated in the accompanying drawings, 25 wherein:—

Figure 1 shows a vertical sectional view of the device shown in expanded position in drilling, and

Figure 2 shows the bit in collapsed position in the process of withdrawal from the well.

Referring now more particularly to the drawings, the numeral 1 designates the well casing which is gradually let down into 35 the bore as drilling progresses. The bit is formed with a barrel, preferably composed of the upper and lower sections 2 and 3 which are screwed together. The upper end of the section 2 is reduced and outwardly threaded and connected to the drill 40 stem 4 by means of the collar 5. Threaded into the lower end of the barrel there is an anchor 6 which has a central spiralled slot 7 extending vertically therethrough. Pivot- 45 ed to opposite sides of the anchor are the outwardly curved side reamers or cutters 8, 8, which have bearings in the anchor in which their pivoted ends are confined by means of a sleeve 9 which is fitted over the 50 anchor 6. These side reamers are pivoted to swing laterally relative to the anchor.

Clamped between the adjacent ends of the barrel sections there is a disc-like guide 10 having a central spiralled slot 11 there- 55 through and the water ports 12, 12 on opposite sides of the slot. A spiralled shank

13 works through the slots 7 and 11. The upper end of this shank has a detachable collar 14 secured thereon by a nut 15 and its lower end is formed into a head 16 which 60 carries the bit 17. This bit may be of any type, a fish tail bit being shown. The head 16 has opposing downwardly flared bearing faces 18, 18 and adjacent them the projecting shoulders 19, 19 which work behind the side 65 reamers 8, 8.

When drilling by the rotary process the bit rests on the bottom of the bore and the weight of the barrel and drill stem holds the anchor 6 against the head 16 and the reamers 70 are held expanded by the sloping faces 18 of the head and are reinforced, during rotation by the shoulders 19. These side reamers, in expanded position, project out underneath the casing and form an enlarged 75 bore sufficient to receive said casing which gradually descends as the bore is made.

When drilling by the cable process a cable is attached to the upper end of the barrel instead of the stem 4, and through it the 80 drill is alternately elevated and dropped. When dropped the bit strikes the bottom of the bore first, and with a rotary or twisting motion, and the barrel and anchor block 85 then descend relative to the head and the side reamers are suddenly projected outwardly by striking the sloping faces 18 and cut into the walls of the bore, also with a rotary motion, and gradually cut away 90 said walls and enlarge the bore, thus underreaming the casing. Upon elevation of the drill the bit remains on the bottom of the bore until the guide 10 strikes the collar 14 and lifts it from said bottom, the bit mean- 95 while rotating to sweep the bottom of the bore clear of cuttings.

When it is desired to withdraw the drill it is elevated through the stem 4, or through the cable, used in lieu thereof. The barrel and anchor 6 will move upwardly, relative to 100 the shank 13 and the bit carried thereby, releasing the faces 18 from the side reamers 8 and permitting them to swing inwardly. The guide 10 will then engage against the collar 14 and the shank and bit will be thereby carried along with the barrel and the entire 105 drill may be thus withdrawn from the bore.

When the drill is to be used as an underreamer a cable 20 is attached to the upper end of the shank 13. This cable extends up 110 to the ground surface and through it the head 16 is held up closely against the anchor

6 and the side reamers thus held expanded and the device may then be held suspended anywhere in the bore and in position to ream out and enlarge the bore by the rotation 5 thereof.

The anchor 6 has suitable water courses 21, 21 therethrough, through which water is admitted to the side cutters to flush them and keep them freed from the formation 10 which may adhere thereto.

What I claim is:—

1. A drill including a barrel, an anchor in the lower end thereof, side cutters carried by said anchor, a spiralled shank operating 15 through a correspondingly shaped bearing in the anchor, and a bit carried by the lower end of said shank.

2. A drill including a barrel, an anchor carried by the lower end thereof and provided with a spiralled bearing therethrough, 20 side cutters pivotally mounted on said anchor, a spiralled shank working through said bearing and having a limited vertical movement relative thereto, and a bit carried by 25 the lower end of said shank.

3. A drill including a barrel, an anchor carried by the lower end thereof and provided with a spiralled bearing therethrough, 30 side cutters pivotally mounted on said anchor, a spiralled shank working through

said bearing and having a limited vertical movement relative thereto, and a bit carried by the lower end of said shank, and means carried by the shank and adapted to engage against and expand said side cutters. 35

4. A drill including a barrel having spiral-shaped bearings therein, a spiralled shank working through said bearings and having a limited lengthwise movement relative to the barrel, expandable side cutters carried by 40 the barrel, a bit carried by the lower end of the shank, and means carried by the shank and adapted to work between and hold said cutters expanded.

5. A drill including a barrel, expandable 45 side cutters carried thereby, a bit having a limited lengthwise movement relative to the barrel, means movable with the bit and adapted to wedge between, and expand, the cutters, and means supporting said bit and 50 formed to impart a rotary movement thereto as it moves relative to the barrel.

In testimony whereof I have signed my name to this specification in the presence of two subscribing witnesses.

GEORGE W. DUNSWORTH.
